(57) **CLAIM**

The ornamental design for a laser alignment tool, as shown and described.

DESCRIPTION

FIG. 1 is a top-front-left perspective view of a laser alignment tool in an exploded configuration showing my new design;

FIG. 2 is a bottom-rear-right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof;

FIG. 8 is a left elevational view thereof;

FIG. 9 is a top-front-left perspective view of the laser alignment tool in an assembled configuration; and,

FIG. 10 is a bottom-rear-right perspective view thereof. The broken lines showing interfacing surfaces in FIGS. 1-9, the broken lines showing fasteners in FIGS. 1-5 and 7-10, the broken lines showing light indicators in FIGS. 1, 3, and 6-9, the broken lines showing base features in FIGS. 1-10, and the broken lines showing laser focusing features in FIGS. 1-5 and 7-10, are included for the purpose of illustrating environmental structure and form no part of the claimed design.
